(57) **CLAIM**

The ornamental design for a lawn light, as shown and described.

DESCRIPTION

FIG. 1 is a perspective view of a lawn light showing my new design;
 FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom side perspective view thereof;

FIG. 9 is a perspective view thereof, showing the lawn light in a separated state;

FIG. 10 is a top view thereof, showing the lawn light in a combined state of use; and,

FIG. 11 is a bottom view thereof, showing the lawn light in a combined state of use.
 The broken lines in the drawings depict portions of the lawn light that form no part of the claimed design.**1 Claim, 11 Drawing Sheets**(56)
